[57] CLAIM

The ornamental design for a heliport floodlight, substantially as disclosed and described.

DESCRIPTION

FIG. 1 is a perspective view of a heliport floodlight showing my new design;

FIG. 2 is a top view thereof on an enlarged scale;

FIG. 3 is a front view thereof on an enlarged scale;

FIG. 4 is a side view thereof on an enlarged scale;

FIG. 5 is a rear view thereof on an enlarged scale;

FIG. 6 is a bottom view thereof on an enlarged scale.
